UNITED STATES PATENT OFFICE.

EUGENE S. ANDERSON, OF BUFFALO, NEW YORK.

DESIGN FOR A BADGE OR SIMILAR ARTICLE.

SPECIFICATION forming part of Design No. 30,386, dated March 28, 1899.

Application filed February 23, 1899. Serial No. 706,591. Term of patent 3½ years.

To all whom it may concern:

Be it known that I, EUGENE S. ANDERSON, a citizen of the United States, residing at Buffalo, in the county of Erie and State of New York, have invented and produced a new and original Design for a Badge, of which the following is a specification, reference being had to the accompanying drawing, forming a part thereof.

10 This design relates to the configuration of a badge or similar article.

The accompanying drawing is a face view of a badge embodying my design.

15 The leading feature of my design consists of the figure of a dust-pan surmounted by the representation of the seal of the State of New York and the figure of a buffalo, which in turn surmounts said seal.

Referring to the drawing, A is the figure of

a dust-pan, standing in an upright position, 20 and b the representation of a pair of small brooms, having their handles crossed on the rear side of the handle of the dust-pan.

C is the representation of the seal of New York State, having the appearance of resting 25 on the dust-pan, and D is the figure of the buffalo, mounted on a base which rests upon the outspread wings of the eagle forming the upper portion of the seal.

What I claim is—

30 The design for a badge or similar article, substantially as herein shown and described.

Witness my hand this 21st day of February, 1899.

EUGENE S. ANDERSON.
